United States Patent Office

Des. 187,404

Patented Mar. 8, 1960

187,404

PORTABLE COOLER

James C. Collord, Alexandria, Ky., assignor to The Heekin Can Company, Cincinnati, Ohio, a corporation of Ohio

Application February 18, 1959, Serial No. 54,673

Term of patent 14 years

(Cl. D67—4)

Fig. 1

Fig. 2

Fig. 4

Fig. 3

Fig. 1 is a perspective view showing one side of my new design for a portable cooler.

Fig. 2 is a perspective view of the opposite side of the portable cooler as it is shown in Fig. 1.

Fig. 3 is a top plan view of the portable cooler shown in Fig. 1.

Fig. 4 is an enlarged sectional view through the top portion of the portable cooler taken on line 4—4 of Fig. 2.

I claim:

The ornamental design for a portable cooler, as shown.
